UNITED STATES PATENT OFFICE.

FRANK T. KNAUSS, OF SCRANTON, PENNSYLVANIA.

IMPROVEMENT IN LAMP-BRACKETS FOR SEWING-MACHINE TABLES.

Specification forming part of Letters Patent No. 179,571, dated July 4, 1876; application filed May 16, 1876.

To all whom it may concern:

Be it known that I, FRANK T. KNAUSS, of Scranton, in the county of Luzerne and State of Pennsylvania, have invented a new and Improved Lamp-Holding Attachment for Sewing-Machines, of which the following is a specification:

My invention consists of a folding lamp-stand, arranged so as to be vertically adjustable on a bracket, which is to be attached to the sewing-machine table by screwing onto the under side. The object of folding the stand is to dispose of it compactly when not in use.

Figure 1 is a front elevation of my improved lamp-holding attachment. Fig. 2 is a sectional elevation taken on line *x x*, Fig. 1; and Fig. 3 is a horizontal section on line *y y*, Fig. 2.

A is the top, and *B* the vertical part, of the bracket, to be attached to the sewing-machine table *C*, (dotted,) as indicated by the screws *D*. *E* is the top, and *F* the vertical part, of the lamp-stand, which are fitted to the bracket

in a groove, so as to slide up and down freely, to be fastened at any required height by the clamp-screw *G*. *H* is a joint in the stand-top, to allow it to fold down out of the way, and *I* is a folding brace, to hold the table up or let it down, at will.

The attachment may be screwed onto the table of the sewing-machine in any convenient place.

Having thus described my invention, what I claim as new, and desire to secure by Letters Patent, is—

The improved lamp-holding attachment for sewing-machines, consisting of the bracket *A* *B*, having a vertical groove and a clamp-screw, and the folding table *E*, folding brace *I*, and the vertical piece *F*, the latter being fitted in the groove of the bracket, and all combined and arranged substantially as specified.

FRANK T. KNAUSS.
